UNITED STATES PATENT OFFICE.

JOHN B. KNAUSS, JR., OF PORTSMOUTH, OHIO, ASSIGNOR TO THE PORTSMOUTH STOVE & RANGE COMPANY, OF PORTSMOUTH, OHIO, A CORPORATION OF OHIO.

HEATER.

Application filed March 31, 1928. Serial No. 266,233.

This invention relates to heaters of the cabinet type, and is particularly directed to the construction and arrangement of the radiator or heating chamber thereof, for a more efficient output of heat.

It is an object of this invention to provide a heater of this type in which the heating chamber, extending from the base of the cabinet to the top thereof is of a lengthened form to provide greater wall surface or area for increased heat radiation.

Another object is to provide a heating chamber or radiator for a cabinet type heater, vertically disposed in the heater cabinet, and having angled upward trend across the path of air travel from the base of the cabinet to the heat openings at the top thereof, sufficiently constricting the path of air travel for proper contact of the air with the increased wall areas of the radiator or heating chamber.

Another object is to reduce the height of the cabinet necessary for a given heat capacity, by the provision of a zigzag form of generally vertically disposed heating chamber or radiator with no reduction in heat radiating surface.

Still another object is to provide a cabinet type heater in which the exterior walls of the cabinet are properly insulated or spaced from the radiator or heating chamber, and in which the arrangement of the heating chamber provides for an even flow of radiated air from all parts of the heater, through the heat opening at the top thereof.

Other objects relate to the general features of construction for ease of assembly in manufacture, and particularly the formation of the radiator and fire chamber unit for convenient incorporation in the heater cabinet.

Further objects and advantages will be more fully set forth in the description of the accompanying drawings, in which:

Figure 1 is a general perspective view of the improved heater, a portion of the front wall of the cabinet being broken away to disclose the radiator unit of the heater.

Figure 2 is a sectional view taken vertically and crosswise through the heater, disclosing in detail the construction and arrangement of the fire chamber and the radiator or heating chamber within the heater casing.

Figure 3 is a sectional view taken on line 3-3, Figure 2, illustrating the upper part of

the radiator and showing the flue opening extending therefrom for exhausting the fumes from the heating chamber, and also showing the baffle interposed in front of the exhaust opening for causing the heat travel to be more uniform and unaffected by the centrally located flue vent.

Figure 4 is a sectional view taken on line 4-4, Figure 2, illustrating the mounting of the gas burners at the base of the fire chamber, and also showing the manner of insulating the fire chamber from the heater side walls.

Referring to the drawings, a rectangular heater casing or cabinet is indicated generally at 1. This casing is open at the top and bottom for the purpose of allowing the necessary air circulation therethrough. The base of the casing is provided with an encircling iron band 2, and legs 3 are provided at each corner thereof. The top of the casing is covered by a cap 4, having a flange 5 overhanging the casing upper edges, this cap being dome-shaped and provided with elongated, vertically disposed heat openings 6.

The radiator or heating chamber and the fire chamber are formed as a unit indicated generally at 7, adapted to be inserted within the outer casing 1. A pair of side walls 8 are provided for this unit, and transversely disposed walls provide the fire chamber and the heating chamber.

The fire chamber 9 is defined by a vertically disposed rear wall 10, spaced away from the rear wall of the casing 1, and a forward extending angled roof 11 extending to a point intermediate of the heater casing, the front wall of the casing 1 providing the forward wall of the fire chamber and the side walls 8 of the unit providing the end walls of the fire chamber, and the base open for the necessary draft.

Parallel walls 12 extend upwardly at a reverse angle respectively from the termination of the roof 11 and the forward wall of the casing 1. These walls continue upward in zigzag formation to a point adjacent the top and rear portion of the casing 1. The transversely parallel extending walls 12, are secured to the side walls 8 by means of turned flanges 13, riveted or spot welded to the side walls.

The chamber or rectangular heat tube formed by the parallel walls 12 is of winding formation or may be said to have an

angled upward trend. A vertically disposed wall 14, closes off the upper end of this zig-zag radiator. Centrally of the vertically wall 14, a flue snout 15, is secured thereto, by means of bolts 16. The wall 14 is spaced away from the rear of the casing 1, and the snout 15, extends across this space and protrudes from the rear of the casing.

A window 16 is provided on the front wall 10 of the fire chamber for observing the condition of the fire. Gas burners 17 traverse the lower portion of the fire chamber and are secured at one end by insertion through the strap iron 2, and at the other end by means 15 of screws 18 passing through an end wall of the fire chamber and axially entering caps at the ends of the burners. Valves 19 are provided at the intake end of the burners for controlling the flow of gas thereinto, from 20 the main feed line 20. A fuel grate basket 21 is hung over the burners by attachment to the end walls of the fire chamber. The fuel basket provides an even flame all through the fire chamber.

25 A baffle plate 22 is mounted between the end walls 8, parallel with and spaced slightly away from the roof of the fire chamber. This baffle plate is of heavy construction for protecting the roof 11 from the deteriorating effect of continual contact with the flames.

The end walls 8 of the radiator or heating end are outwardly flanged as at 23, (see Figure 3), these flanges engaging the front and rear walls respectfully of the casing 1. 35 Spaces 24 are thus provided at each side of the heating unit for insulating the casing side walls from the radiator walls. Apertures 25 connect the space between the transversely extending walls 12 and the front casing 40 walls 1 with the insulating spaces at the respective side walls of the casing.

The cold air intake for the heater is through the open base end thereof, the air flowing upwardly through the before mentioned connected spaces to the top of the casing and during the course of its travel therefrom being subjected to contact with the walls of the radiator. In order to provide that there will be no constriction of air travel from the base 45 to the top of the casing the zigzag radiator is of general narrower width at the top than at the lower end thereof.

Since the exhaust vent or snout 15, is disposed centrally of the upper end of the radiator or heat tube, the tendency of the products of combustion would be to travel through the zigzag radiator in the form of a cone to this centrally disposed opening. In order to provide that the heat flow through this radiator will be in parallel lines and consequently evenly distributed, a baffle 26 is inserted across the upper end of the radiator, parallel to the rear wall 14 and slightly spaced away from that wall within the radiator, this baffle stopping short of the walls 8 for providing the 65 end passageways 27.

This arrangement of the radiator walls produces a greater amount of heat from a given source and the heater is much more compact than the conventional type.

Having described my invention, I claim:

1. A heater construction, comprising, a rectangular cabinet casing open at the top and bottom for air circulation therethrough, an inner casing mounted within said rectangular casing, said inner casing comprising side plates, said side plates being spaced from the end walls of the outer casing and transversely extending walls between said side plates providing a large fire chamber at the base of the casing and a zigzag heating chamber extending upwardly from the fire chamber to an upper corner of the heater, means for exhausting the fumes from said heating chamber, and said side plates apertured to connect the spaces between the end plates and the end walls of the cabinet casing with the spaces at each side of the heating chamber.

2. In combination with a casing open at the top and bottom, a heater unit for insertion in said casing, said heater unit, comprising, end plates having outwardly turned flanges along their side edges, spaced walls secured transversely between said plates, said walls constituting a fire chamber at the lower end and a zigzag heating chamber extending upwardly therefrom, means for exhausting the fumes from said heating chamber, and said plates having apertures through those portions thereof not constituting the 100 heating chamber end walls.

In witness whereof, I hereunto subscribe my name.

JOHN B. KNAUSS, JR.
